UNITED STATES PATENT OFFICE.

WILLIAM E. VAN DORN, OF CHICAGO, ILLINOIS.

METAL WALL FOR RAILWAY CARS AND THE LIKE.

Application filed April 17, 1922, Serial No. 553,981. Renewed March 4, 1926.

In recent years freight cars have quite generally been provided with metal ends made out of sheet metal corrugated in various ways to secure stiffness. In manufacturing a corrugated sheet in which the corrugations are pressed out of the plane of flat portions lying in the original plane of the sheet, the metal in the corrugations is weakened by being reduced in thickness, and there is considerable waste because of the distortion of the sheet and the consequent necessity of trimming the same after it has been corrugated. Furthermore, at least three or four operations, including heating of the sheets as it is almost impossible to corrugate them in a cold state, are required for manufacturing corrugated metal ends, making the process slow and expensive.

One of the objects of the present invention is to produce a simple and novel reinforced panel or sheet which shall be more rigid than a similar corrugated sheet on account of more advantageous placing of the metal in the stiffening ribs.

A further object of the present invention is to produce a simple and novel reinforced metal panel or sheet having stiffening ribs so formed as to avoid the waste which results from the drawing in of the metal to form the corrugations, in a sheet or panel having flat marginal portions at the ends of the corrugations, and the consequent necessity of trimming the edges of the sheet or panel after the latter has been corrugated.

A further object of the present invention is to produce a simple and novel reinforced metal panel or sheet having flat marginal portions and reinforcing ribs in such a manner that each panel may be finished by simple operations and without the necessity of heating the panel.

In carrying out my invention, I simply punch or shear through a sheet of the desired size or shape and then bend some of the metal bordering the perforation, cut or slit so as to lie at an angle to the plane of the sheet and form a reinforcing rib or ribs. It will be seen that by this process there need be no distortion of the peripheral contour of the sheet, because the reinforcing elements are simply punched or sheared and then bent so as to lie at an angle to the plane of the sheet, there being no drawing in of the metal as in the case of a sheet having corrugations lying between flat marginal portions. As a matter of fact, a finished flanged panel may

be formed in simple operations out of a sheet cut to a predetermined size and shape. The shearing and bending of the ribs is a much simpler operation than the pressing of a corrugation completely surrounded by a flat marginal section and can therefore be performed more quickly and with less expenditure of energy than the latter. Since it is not necessary to trim the sheet because of any distortion produced in forming the reinforcing ribs, no material is wasted; since the waste in connection with corrugated sheets results from the drawing of metal from the flat marginal portions to form the corrugations, there is a further saving in my improved sheet equal to the amount of metal required to complete the corrugations in the corrugated sheet; and since the metal in the reinforcing ribs has not been stretched as it has in the corrugations, and since the disposition of the metal in the reinforcing ribs is not limited to certain specific forms or contours as in the case of the metal in the corrugations, a much stiffer, more effectively reinforced, and more efficient sheet may be obtained than is possible in the case of corrugated sheets. Furthermore, there is a definite limit to the number of corrugations which can be pressed into a sheet and a definite limit to the size of a sheet which may be corrugated, without tearing. According to my invention there is no limit as to size or number of the stiffening ribs or as to the size of the sheet which may be reinforced by means of such ribs; in fact, the whole side of a car might, if desired, be made out of a single sheet or panel.

While my invention may be used in other places, it is particularly applicable to metal car ends and therefore specifically considered, the present invention may be said to have for its object to produce a simple and novel steel end which will be stronger, lighter and cheaper to manufacture than a corrugated steel end of the same size and made out of the same material.

There is another advantage possessed by my invention over corrugated panels or ends. It is a requirement of the majority of railroads that corrugated steel ends be lined on the inner side with wooden sheathing or flat metal plates. The contact between the metal of the ends and the lining is along the ridges of the corrugations on the inner side of the metal end, making substantially a series of line contacts between the end and the

lining. Furthermore, these lines of contact are spaced apart distances equal to the distance from the center of one corrugation to the center of the next corrugation. In my arrangement the inner side of the metal end may remain perfectly flat so that the end and the lining engage with each other, not along a few lines, but over the entire surface of the end less the combined areas of the openings produced in the formation of the strengthening ribs. Furthermore, the lining has no unsupported portion between lines of contact with the end of a span greater than the width of the slots or openings in the metal end as contrasted with a free span equal to the distance between the center of one corrugation and the center of the next in a corrugated sheet. In practice, where parallel elongated reinforcing ribs are employed, the depth thereof will ordinarily be not greater than one-half the distance between the centers of the corrugations of a corrugated end, bringing about such a relation between the length of span between points of support and the thickness of the lining that the failure of the lining must come about through an actual shearing of the lining as distinguished from a failure through bending. Therefore the lining which is employed in connection with my improved metal end may be made lighter than that required for corrugated ends, if no greater strength be required or, if made of the same thickness as the lining employed with a corrugated metal end, will result in a much stronger construction than one in which a corrugated metal end is employed.

The various features of novelty whereby my invention is characterized will herein after be pointed out with particularity in the claims; but, for a full understanding of my invention and of its objects and advantages, reference may be had to the following detailed description taken in connection with the accompanying drawings, wherein:

Fig. 1 is an end view of a railway box car having a metal end constructed and arranged in accordance with the present invention;

Fig. 2 is a section taken approximately on line 2—2 of Fig. 1;

Fig. 3 is a section taken approximately on line 3—3 of Fig. 1;

Fig. 4 is a view similar to Fig. 1, illustrating a gondola car;

Fig. 5 is a section taken approximately on line 5—5 of Fig. 4;

Fig. 6 is an elevation of a fragment of an end or panel having a slightly modified form of reinforcing rib;

Fig. 7 is a section taken approximately on line 7—7 of Fig. 6;

Fig. 8 is an elevation of a fragment of an end or panel in which the ribs have a still different form;

Fig. 9 is a section taken approximately on line 9—9 of Fig. 8;

Fig. 10 is a view similar to Fig. 9, that is a section through a fragment of a panel or sheet at right angles to the ribs, showing a still further modification;

Figs. 11, 13 are end views of box cars equipped with still other forms of ends embodying my invention;

Fig. 12 is a section on line 15—15 of Fig. 13;

Fig. 14 is a view similar to view 8, showing a still further modification; and Fig. 15 is a section taken approximately on line 18—18 of Fig. 14.

In the drawings I have illustrated my invention as applied to complete ends for box cars or gondola cars; and, for the sake of brevity, I shall confine the detailed description to the particular embodiments illustrated although it will of course be understood that my invention, as viewed in some of its aspects, is not limited to complete car ends or to car end panels.

In Figs. 1 to 3 of the drawings I have illustrated a steel end made of two panels 1 and 2 arranged one above the other and fastened together at their meeting edges by means of a lap joint 3. The ends of the panels are flanged inwardly as indicated at 4, so as to fit around the corners between the end and the sides 5. The lower panel may be flanged outwardly, as indicated at 6, so as to provide a foot member adapted to rest upon and be secured to a suitable end sill 7. All of the features to which I have just referred may of course be varied in many different ways.

In accordance with my invention I cut slits into each of the panels and bend portions adjacent thereto out of the plane of the sheet so as to form reinforcing ribs. In the arrangement shown, these slits are arranged parallel with each other, they are made to extend transversely of the panels, and they extend from points near one side of the car body to points near the other side of the car body. Each slit follows a horizontal central line 8 and inclined end walls 9 and 10 extending upwardly and outwardly from the ends of the line 8. The parts 8 constitute the major portions of the slits, while the parts 9 and 10 constitute simply short end sections. The short wide tongues 11 which are produced by cutting the slits are then bent outwardly along lines parallel with the lines 8 until they project at right angles to the original plane of the sheet. It will be seen that by this arrangement I secure a series of parallel webs or ribs extending across the car end from one corner post to the other. It will also be seen that one of the ribs in either of the two panels, or a rib in each panel, may be placed immediately adjacent to the joint between the

panels, thus strengthening the end at the point which is usually the weakest in a two-piece end. In the same way, regardless of the direction in which the joint or joints extend, such joint or joints may be reinforced by strengthening ribs running along the same. These webs or ribs may extend at any angle to the plane of the end, preferably at right angles; and they may be simple straight pieces or, as shown at 11^a in Fig. 10, each may be bent along a line extending lengthwise through the same so as to form in effect a series of Z-bars.

Lying behind and engaged with the steel end is a wooden lining or sheathing 12. This lining may conveniently be made of vertical boards. In order to fasten the metal end and the lining together there may be placed on the outer side of the metal end, between consecutive ribs, as many heavy boards or planks 13 as may be desired; each board or plank fitting between and extending throughout the lengths of two adjacent reinforcing ribs. Elements corresponding to the members 13 may be employed in connection with the other forms of my invention, as well. The wooden lining may be attached to the member 13 by means of nails, screws or other fastening means 14, passing through the lining, through the openings left in the metal end when the ribs are bent up, and into the planks 13. By this arrangement the wooden lining and the metal end are drawn tightly together so as to prevent the entrance of foreign matter between them. It will be seen that the members 13 close the holes in the metal end produced by the bending out of an equal number of ribs. Therefore, if desired, all of the openings may be closed by simply placing a plank or a board between each pair of consecutive ribs. It will be seen that the metal end has a broad bearing surface on the wooden lining, the area of contact being, in the arrangement shown, perhaps one-half of the entire area of the end. Furthermore, the unsupported sections of any one of the vertical boards of the lining are quite short so that the boards of which the lining is made can be much lighter than would be the case if they were supported only at intervals along lines corresponding in spacing to the ribs, as is the case where a corrugated metal end and a lining are engaged with each other.

In Figs. 4 and 5, I have shown an end for a gondola car made out of a single panel 15 similar to the panel 2 in the box car. The panel 15 is provided with ribs 11 formed in the manner heretofore described; and the wooden lining 16, placed on the inner side of the metal end, is fastened thereto by means of suitable fastening means 14 passing through the holes in the steel end and into heavy boards or planks 13 as in the

box car construction. Vertical angle irons 17 may be placed in the corners between the lining and the side walls 18 of the car. An angle iron 19 may be placed along the upper edge of the steel end, one of its flanges being horizontal and the other being vertical and lying between the steel end and the lining.

While I prefer to form the ribs without doing more than simply bending the partially detached short wide tongues after the slitting or shearing operation, some of the advantages of my invention may be obtained even though there should be some stretching or drawing of metal in the production of the ribs. Thus in Figs. 6 and 7, I have shown a panel 20 in which the ribs are formed by first cutting a series of parallel slits 21 in the sheet and then bending the metal on one side of each slit outwardly midway between the ends of the slit to form a rib 22 approximately at right angles to the sheet. The part 22 may be of any desired length, merging at its ends gradually into diagonal web or flange portions 23 which may lie approximately in vertical planes symmetrically disposed at a small angle to each other on opposite sides of the center of the panel; the extreme outer ends of the members 23 disappearing in the plane of the sheet.

If the part 22 of the rib be made almost as long as the corresponding slit, a condition will be produced such as shown in Figs. 8 and 9 in which the panel 24 has straight ribs 25 approximately as long as the slits 26 so that the ends of the ribs terminate in short downwardly-extending webs 27.

In Fig. 11, I have shown an arrangement in which an end for a box car is made of two panels 28 and 29 fastened together by a vertical lap joint 30 at the center of the end. The ribs 31 are similar to the ribs 11 heretofore described, but are arranged vertically instead of horizontally.

In Fig. 13 there are three panels, a central panel 37, and side panels 38 and 39; the three panels being fastened together by lap joints 40. The central panel has vertical ribs 41 extending from top to bottom, and the side panels have short horizontal or transverse ribs 42. The side edges of the central panel may be bent or flanged outwardly, as indicated at 43, to form reinforcing ribs for the joints. The general shape of the beams formed by the ribs and the adjacent flat portions of the sheet, as heretofore illustrated, has been that of an angle bar or a Z-bar. If desired, the beams, or some of them, may take the form of channels. Thus, the two central ribs in the middle panel in Fig. 13 both lie adjacent to an imperforate central section 44 which, as shown in Fig. 12, forms with the two adjacent ribs 41 a channel beam. Instead of

having a wooden lining for the metal end, the lining may be made of metal in the form of a simple sheet as indicated at 45 in Fig. 12 or in any other suitable form.

In all of the forms of reinforcing ribs heretofore illustrated each rib or flange has had at the base a flanged portion arranged at an angle thereto and constituting a part of the metal lying in the original plane of the sheet. It is possible, however, so to slit a sheet that when the ribs are bent out of the plane thereof there will be no metal left in its original position except at the margins. In other words, the panel will consist of a frame or frames across which extend a series of flat slats arranged on edge. Such a construction is shown in Figs. 14 and 15 in which the sheet 48 has been slit in such a manner that the central portion thereof could be transformed into a series of independent slats or bars supported at their ends only.

I claim:

1. A wall for a car comprising a metal panel, a lining lying behind and against said panel, said panel having sections partially severed therefrom and bent outwardly at an angle to the panel to form stiffening ribs adjacent to openings extending through the panel, and means passing through said openings for fastening said panel and said lining together.

2. A wall for a car comprising a metal panel, a lining lying behind and against said panel, said panel having sections partially severed therefrom and bent outwardly at an

angle to the panel to form stiffening ribs adjacent to openings extending through the panel, beams lying against the outside of the panel adjacent to at least some of said ribs and overlapping solid portions of the panel beside corresponding openings therein, and means extending through the latter openings to fasten the lining and beams together and clamp the panel between them. 45

3. A wall for a car comprising a metal panel, a lining lying behind and against said panel, said panel being slitted and having sections bordering the slits bent outwardly at an angle to the panel to form stiffening ribs adjacent to openings extending through the panel, and means passing through said openings for fastening said panel and said lining together. 50

4. A wall for a car comprising a metal panel, a lining lying behind and against said panel, said panel being slitted and having sections bordering the slits bent outwardly at an angle to the panel to form stiffening ribs adjacent to openings extending through the panel, beams lying against the outside of the panel adjacent to at least some of said ribs and overlapping solid portions of the panel beside corresponding openings therein, and means extending through the latter openings to fasten the lining and beams together and clamp the panel between them. 60 65

In testimony whereof, I sign this specification.

WILLIAM E. VAN DORN.
